UNITED STATES PATENT OFFICE.

WILLIAM C. SPIETH, OF GENEVA, OHIO.

ARC LAMP.

Application filed June 24, 1927. Serial No. 201,154.

My invention relates to arc lamps, and particularly to reflectors for arc lamps, and the principal object of my invention is to provide a new and improved reflector particularly adapted for this purpose. In the drawings accompanying this specification and forming a part of this application, I have shown, for purposes of illustration, one form which my invention may assume, and 10 in these drawings:

Figure 1 is a front elevation showing the embodiment of my invention herein illustrated,

Figure 2 is a section on the line 2—2 of 15 Figure 1, while

Figure 3 is a section on the line 3—3 of Figure 1.

Herein I have shown my invention as applied to an arc lamp 11 comprising an upper 20 mechanism section 12 from which rise terminals 13 and 14, through which the entire lamp is supported by means of a hanger 15, and from which depend a pair of rods 16 supporting a frame 17 which carries on its 25 lower face an insulating disc 18 centrally apertured for the passage of the upper carbon 19 therethrough, is provided on its two sides with outwardly extending arms 20 provided at their ends with apertured 30 lugs 21 adapted to receive insulating bushings 22 through which pass supporting and conducting rods 23 insulated from the frame 17 by means of the insulating bushings 22, held in position by means of nuts 24 flanking 35 the insulating bushings 22, connected to a conductor 25 leading from one side of the line, surrounded by insulating tubes 26, and supporting at their lower ends a cross bracket 27 in which is mounted the lower 40 carbon 28.

The embodiment of my invention herein shown comprises a reflector 30 formed in two parts, a front part 31, and a rear part 32.

The front reflector section 31 comprises a 45 top 33, a base 34, and a curved lateral wall 35 secured to the top 33 and the base 34, interrupted centrally, and provided at the edges of the interruption with projections 36 extending to engage the tubes 26 on the rear 50 surface thereof to maintain the reflector section 31 supported from the tubes 26 quickly removable therefrom because of the resiliency of the extensions 36, extending then forwardly about the tubes 26, and finally 55 terminating in lips 37; while the rear reflector section 32 comprises a lateral wall por-

tion 38 provided at its edges with lips 39 adapted to interengage the lips 37 of the front reflector section 31, and formed resilient to permit the lips 39 being moved into and out of interengagement with the lips 37 to permit ready attachment of the rear reflector section 32 to the front reflector section 31, and ready detachment of the rear reflector section 32 from the front reflector section 31. The rear reflector section 32 however extends downwardly below the front reflector section 31, and is provided at its lower end with an integral table 40 extending beneath the arc to catch any material dropping 70 from the arc.

It will of course be understood by those skilled in the art that the reflector sections 31 and 32 may be made conveniently by stamping.

From the above description it will be obvious to those skilled in the art that I have provided a reflector particularly adapted for arc lamps, readily attachable and detachable, and economical to manufacture, and it therefore will be apparent that the embodiment of my invention herein shown and described accomplishes at least the principal object of my invention. At the same time those skilled in the art will appreciate that the embodiment of my invention herein shown and described embodies advantages and uses other than those specifically set forth or suggested herein, and may be variously changed and modified without departing from the spirit 85 of my invention or sacrificing these advantages and uses, and it therefore will be understood that the disclosure herein is illustrative only, and that my invention is not limited thereto.

I claim:—

1. A reflector for use with an arc lamp of a type having vertically extending members flanking the arc on the two sides of the arc, comprising a top, a base, and a lateral wall 100 connecting said top and said base, and provided with resilient fingers adapted to resiliently clamp said members to hold said reflector supported on said lamp quickly detachable therefrom.

2. A reflector for use with an arc lamp of a type having vertically extending members flanking the arc on the two sides of the arc, comprising a top, a base, and a lateral wall 110 connecting said top and said base and provided with resilient fingers adapted to resiliently clamp said members to hold said re-

flector supported on said lamp quickly detachable therefrom.

3. A reflector for use with an arc lamp of a type having vertically extending members flanking the arc on the two sides of the arc, comprising a top, a base, and a lateral wall connecting said top and said base interrupted centrally and provided at the edges of said interruption with resilient fingers adapted to resiliently clamp said members to hold said reflector supported on said lamp quickly detachable therefrom.

4. An arc lamp reflector comprising a front section, and a rear section, said sections being provided with lips adapted when interengaged to secure said sections together supported one from the other, and one of said sections being resilient to permit that section to be sprung to permit said lips to be so interengaged.

5. An arc lamp reflector comprising a front section supported from the arc lamp, and a rear section, said sections being provided with lips adapted when interengaged

25 to secure said sections together with said rear section supported from said front section, and one of said sections being resilient to permit that section to be sprung to permit said lips to be so interengaged.

30 6. An arc lamp reflector comprising a front section, and a rear section, said sections being provided with lips adapted when interengaged to secure said sections together supported one from the other, and said rear section being resilient to permit that section to be sprung to permit said lips to be so interengaged.

40 7. An arc lamp reflector comprising a front section supported from the arc lamp, and a rear section, said sections being provided with lips adapted when interengaged to secure said sections together with said rear section supported from said front section, and said rear section being resilient to permit that section to be sprung to permit said lips to be so interengaged.

45 8. An arc lamp reflector provided with a depending extension carrying a table positioned beneath the arc to catch material dropping from the arc.

50 9. An arc lamp reflector provided with a depending extension integral with and depending from the rear part of said reflector and carrying a table positioned beneath the arc to catch material dropping from the arc.

55 10. A reflector for use with an arc lamp of a type having vertically extending members flanking the arc on the two sides of the arc, comprising: a front section, and a rear section; said front section including a top, a base, and a lateral wall connecting said top and said base, and being provided with resilient fingers adapted to resiliently clamp said members to hold said front section supported on said lamp quickly detach-

able therefrom; said sections being provided with lips adapted when interengaged to secure said sections together with said rear section supported from said front section; and one of said sections being resilient to permit that section to be sprung to permit said lips to be so interengaged.

11. A reflector for use with an arc lamp of a type having vertically extending members flanking the arc on the two sides of the arc, comprising: a front section, and a rear section; said front section including a top, a base, and a lateral wall connecting said top and said base and provided with resilient fingers adapted to resiliently clamp said members to hold said front section supported on said lamp quickly detachable therefrom; said sections being provided with lips adapted when interengaged to secure said sections together with said rear section supported from said front section; and one of said sections being resilient to permit that section to be sprung to permit said lips to be so interengaged.

12. A reflector for use with an arc lamp of a type having vertically extending members flanking the arc on the two sides of the arc, comprising: a front section, and a rear section; said front section including a top, a base, and a lateral wall connecting said top and said base interrupted centrally and provided at the edges of said interruption with resilient fingers adapted to resiliently clamp said members to hold said front section supported on said lamp quickly detachable therefrom; said sections being provided with lips adapted when interengaged to secure said sections together with said rear section supported from said front section; and one of said sections being resilient to permit that section to be sprung to permit said lips to be so interengaged.

13. A reflector for use with an arc lamp of a type having vertically extending members flanking the arc on the two sides of the arc, comprising: a front section, and a rear section; said front section including a top, a base, and a lateral wall connecting said top and said base, and being provided with resilient fingers adapted to resiliently clamp said members to hold said front section supported on said lamp quickly detachable therefrom; said sections being provided with lips adapted when interengaged to secure said sections together with said rear section supported from said front section; and one of said sections being resilient to permit that section to be sprung to permit said lips to be so interengaged.

14. A reflector for use with an arc lamp of a type having vertically extending members flanking the arc on the two sides of the arc, comprising: a front section, and a rear section; said front section including a top, a base, and a lateral wall connecting said top

and said base and provided with resilient fingers adapted to resiliently clamp said members to hold said front section supported on said lamp quickly detachable therefrom; 5 said sections being provided with lips adapted when interengaged to secure said sections together with said rear section supported from said front section, said rear section being resilient to permit that section to be sprung 10 to permit said lips to be so interengaged.

15. A reflector for use with an arc lamp of a type having vertically extending members flanking the arc on the two sides of the arc, comprising: a front section, and a rear section; 15 said front section including a top, a base, a lateral wall connecting said top and said base interrupted centrally and at the edges of said interruption provided with resilient fingers adapted to resiliently clamp 20 said members to hold said front section supported on said lamp quickly detachable therefrom; said sections being provided with lips adapted when interengaged to secure said sections together with said rear 25 section supported from said front section; said rear section being resilient to permit that section to be sprung to permit said lips to be so interengaged.

16. An arc lamp reflector comprising a 30 front section, a rear section, and a depending extension, said sections being provided with lips adapted when interengaged to secure said sections together supported one from the other, one of said sections being resilient 35 to permit that section to be sprung to permit said lips to be so interengaged, and said extension depending integrally from said rear section and carrying a table positioned beneath the arc to catch material dropping from the arc.

40 17. An arc lamp reflector comprising a

front section supported from the arc lamp, a rear section, and a depending extension, said sections being provided with lips adapted when interengaged to secure said sections together with said rear section supported from 45 said front section, one of said sections being resilient to permit that section to be sprung to permit said lips to be so interengaged, and said extension depending integrally from 50 said rear section and carrying a table positioned beneath the arc to catch material dropping from the arc.

18. An arc lamp reflector comprising a 55 front section, a rear section, and a depending extension, said sections being provided with lips adapted when interengaged to secure said sections together supported one from the other, said rear section being resilient to permit that section to be sprung 60 to permit said lips to be so interengaged, and said extension depending integrally from said rear section and carrying a table positioned beneath the arc to catch material dropping from the arc.

19. An arc lamp reflector comprising a 65 front section supported from the arc lamp, a rear section, and a depending extension, said sections being provided with lips adapted when interengaged to secure said sections together with said rear section supported from 70 said front section, said rear section being resilient to permit that section to be sprung to permit said lips to be so interengaged, and said extension depending integrally from 75 said rear section and carrying a table positioned beneath the arc to catch material dropping from the arc.

In testimony whereof I hereunto affix my 80 signature.

WILLIAM C. SPIETH.
